EUGEN PRESTINARI, OF PAWTUCKET, RHODE ISLAND, ASSIGNOR TO NEW JERSEY CHAIN CORPORATION, OF NEWARK, NEW JERSEY, A CORPORATION OF NEW JERSEY.

BRACELET HOOK.

Application filed July 12, 1926. Serial No. 121,842.

This invention relates to an improved construction of bracelet hook or end member; and has for its object to provide a device of this character having a body portion in which one end of a hook member is pivotally mounted the hook being acted upon by a spring pressing it to operating position.

A further object of the invention is the provision of a fixed tongue on the body for closing the hook whereby the hook itself must be swung away from the closing tongue in order to permit the hook to be connected and disconnected.

With these and other objects in view, the invention consists of certain novel features of construction, as will be more fully described, and particularly pointed out in the appended claims.

In the accompanying drawings:

Figure 1 is a perspective view illustrating my improved hook as connected to one of the bails of a watch.

Figure 2 is a perspective view showing the body of the hook, or end member.

Figure 3 is a perspective view showing the hook member of the device.

Figure 4 is a perspective view showing the pivot pin with the operating spring wound about it.

Figure 5 shows the hook member as pivotally mounted in the body with the spring acting to press the hook towards closed position.

Figure 6 shows the hook as swung on its pivot to open position away from the fixed tongue.

Figure 7 is a section on line 7-7 of Figure 5 showing the hook pivotally mounted in the body member.

Figure 8 is a perspective view illustrating the hook as being swung into position to engage or disengage the bail of a watch, the fingers of the operator being shown in dotted lines as engaging the sides of the body portion and the back of the hook member.

It is found in the practical operation of some styles of bracelet hooks, difficult to disengage the same from a watch bail, some requiring one finger to be inserted beneath the hook to raise the tongue in order to release the same which is difficult particularly when on the arm of the wearer, and which difficulty I have overcome in a simple and

practical way by pivoting the hook member, instead of the tongue member, in the body portion of the device whereby it is only necessary to engage the sides of the body between the thumb and finger with one finger on the back of the hook to swing them relatively and open the hook for ready engagement or disengagement; and the following is a detailed description of the one construction of my improved hook by which these advantageous results may be accomplished:

With reference to the drawings, 10 designates the body of the hook which is preferably formed from a blank of sheet stock 70 folded into box form having a top wall 11, bottom wall 12, and side walls 13. In some cases one end wall 14 may be provided to which the next adjacent bracelet element 15 may be attached when desired. 75

The bottom wall is provided at its open end with a forwardly projecting tongue 16 which may be formed integral with this wall if desired for the purpose of closing the hook. 80

The hook member 17 of this device is also preferably formed of sheet stock being folded at one end to form an engaging hook or loop 18 preferably broader than the body member of the device to engage and fit 85 closely in the bail 19 of a watch 20.

The opposite end of this hook is preferably reduced as at 21 forming a neck portion which is provided on its opposite edges with downwardly extending ears 22 pierced as at 23 and this neck portion is arranged to fit between the side walls of the box member 10 and is pivotally secured thereto by means of a pivot pin 24 which preferably extends through the ears 22 and 90 through the pierced walls 13 of the box portion. 95

In order to press this hook member up into alignment with the front wall of the box member, I have provided a coiled spring 100 25 which is wound about the pivot pin 24, its opposite ends acting upon the under side of the hook and the inner face of the bottom wall 12 of the body by means of which this hook is pressed upward to lie against the 105 inner face of the upper 11 of the body bringing its extremity 26 into proximity with the end of the closing tongue 12, whereby it becomes necessary to swing this hook portion 110 downwardly relative to the tongue as best

shown in Figure 6, to open the hook and permit the passage of the bail or other article to which it is to be attached into and out of the hook.

I have described the tongue portion which is carried on the body member as being rigid, requiring a relative disengaging movement of the hook in attaching the same, but I may in some cases make the tongue 10 resilient to yield and permit an engaging action without being obliged to swing the hook if desired.

The device is very simple and practical in construction, is effective in its operation 15 and its opposite sides may be readily engaged by the fingers of the operator of the hook and the hook itself pressed downwardly to effect either a connecting or disconnecting action to and from its operating 20 position.

The foregoing description is directed solely towards the construction illustrated, but I desire it to be understood that I reserve the privilege of resorting to all the mechanical changes to which the device is susceptible, the invention being defined and limited only by the terms of the appended claims. 25

I claim:

1. A bracelet end member having a sheet 30 metal body portion and a sheet metal hook member pivoted to said body portion, said hook being opened by swinging of the hook towards its free edge relative to the body.

2. A bracelet end member having a body 35 portion, a hook member pivoted to said body portion, a hook-closing tongue carried by the body and engageable with the inside of said hook to close the same when in oper-

ative position, said hook being movable to cause its neck to move towards said tongue 40 to open the hook.

3. A bracelet end member having a sheet metal box shaped body portion, a separate hook member pivoted at one end in said box and a hook closing tongue rigidly carried by said body and engaging the inside of said hook to close the same. 45

4. A bracelet end member having a body portion, a hook member pivoted in said body and swingable towards its free edge relative to said body to open position and a spring acting between the body portion and the hook to normally press it to closed position. 50

5. A bracelet end member having a body 55 portion, a hook member pivoted in said body portion, a spring acting between the hook and the body portion to press it to closed position, and a tongue fixed on the body and engaging the inside of said hook to 60 close the same.

6. A bracelet end member comprising a sheet metal hollow body with top, bottom and side walls, a hook member having a neck portion pivoted between the side walls of 65 said body, a tongue on said bottom wall extending outwardly to close the mouth of the hook member, and a spring pressing said hook member and tending to cause its end to lie adjacent the end of said tongue thereof, said hook being movable towards said tongue to open said hook. 70

In testimony whereof I affix my signature.

EUGEN PRESTINARI.
